CLAIM

The ornamental design for a catcher for a door closer, as shown and described.

DESCRIPTION

FIG. 1 is a front elevational view of a catcher for a door closer showing my new design;

FIG. 2 is a top plan view thereof;

FIG. 3 is a bottom plan view thereof;

FIG. 4 is a right side elevational view thereof;

FIG. 5 is a left side elevational view thereof;

FIG. 6 is a sectional view taken along line 6—6 of FIG. 2;

FIG. 7 is a sectional view taken along line 7—7 of FIG. 2;

FIG. 8 is a sectional view taken along line 8—8 of FIG. 2;

FIG. 9 is a front elevational view thereof, with the protruded portion shown in retracted position; and,

FIG. 10 is a perspective view thereof, shown the article in its environmental use.

The broken lines showing an environment in FIG. 10 is for illustrative purpose only and forms no part of the claimed design.
